CLAIM

The ornamental design for a water line manifold guard, as shown and described.

DESCRIPTION

FIG. 1 is a front perspective view of a water line manifold guard shown in a position of use with environmental fluid conduits;

FIG. 2 is a front perspective view of the water line manifold guard shown in FIG. 1;

FIG. 3 is a front elevation view of the water line manifold guard shown in FIG. 1;

FIG. 4 is a rear elevation view of the water line manifold guard shown in FIG. 1;

FIG. 5 is a top plan view of the water line manifold guard as shown in FIG. 1;

FIG. 6 is a bottom plan view of the water line manifold guard as shown in FIG. 1;

FIG. 7 is a left lateral elevation view of the water line manifold guard as shown in FIG. 1; and,

FIG. 8 is a right lateral elevation view of the water line manifold guard as shown in FIG. 1.

The dashed broken lines shown depict environmental matter only and form no part of the claimed design.

1 Claim, 3 Drawing Sheets
